The dominant portions of my design are shown in full lines on the drawing.

I claim:

The ornamental design for a doll or similar article, substantially as shown and described.
